Des. 225,230

Patented Nov. 28, 1972

225,230

DENTAL OPERATORY UNIT

H. John Kretschmer, New York, N.Y., assignor to
Modumatic Industries, Inc.

Filed Sept. 23, 1971, Ser. No. 183,295

Term of patent 14 years

Int. Cl. D24—01

U.S. Cl. D24—1

F/G. I

FIG. 1 is a front and right side perspective view of a dental operatory unit embodying my new design;

FIG. 2 is a rear elevational view thereof; and

FIG. 3 is a left side elevational view thereof.

I claim:

The ornamental design for a dental operatory unit, as shown.
